TELEPHONE DESK

Oscar Torgerson, Portland, Oreg.

Application February 13, 1951, Serial No. 14,194

Term of patent 7 years

(Cl. D33—7)

To all whom it may concern:

Be it known that I, Oscar Torgerson, a citizen of the United States, residing at Portland, county of Multnomah, and State of Oregon, have invented a new, original, and ornamental Design for Telephone Desk, of which the following is a specification, reference being had to the accompanying drawing, forming a part hereof.

Fig. 1 is a front perspective view of a telephone desk, showing my new design; and

Fig. 2 is a reduced rear perspective view of the same.

I claim:

The ornamental design for a telephone desk, as shown.

OSCAR TORGERSON.
